US00D598744S

(12) **United States Design Patent**
Shields

(10) **Patent No.:** **US D598,744 S**
(45) **Date of Patent:** ** *Aug. 25, 2009

(54) **COMBINED POUCH AND TUB MIX**

(75) Inventor: **Frank Shields**, Nashville, TN (US)

(73) Assignee: **MARS, Incorporated**, McLean, VA
(US)

(**) Term: **14 Years**

(21) Appl. No.: **29/331,522**

(22) Filed: **Jan. 27, 2009**

Related U.S. Application Data

(62) Division of application No. 29/287,522, filed on Aug. 17, 2007, now Pat. No. Des. 587,568.

(51) **LOC (9) Cl.** **09-03**

(52) **U.S. Cl.** **D9/428; D9/425**

(58) **Field of Classification Search** **D9/414–415, D9/418, 423–429, 431–432, 435, 452–453, D9/515, 761; D7/354, 360, 504, 500, 538, D7/540, 543, 545, 550.1, 553.6, 554.2, 557, D7/565, 584–585, 602, 629, 672; D3/201, D3/203.1–203.3, 284, 294, 295, 304, 307–314; 220/4.21–4.24, 23.8, 23.87, 266, 276, 345, 220/377, 532–533, 655, 675, 781–784, 787, 220/790–791, 793, 835; 206/45.19, 45.32, 206/386, 425, 438, 470, 503, 508, 509, 511, 206/518–521, 541, 555, 558, 560, 564, 625, 206/643; 229/120, 125, 406; 426/106, 119, 426/129, 234; 219/734**
